PHONOGRAPH RECORD RESURFACING MACHINE

Louis Z. LaForest, Orange, N. J., assignor to
Thomas A. Edison, Incorporated, West Orange,
N. J., a corporation of New Jersey

Application April 26, 1939, Serial No. 270,109

24 Claims.

(Cl. 82—1.1)

This invention relates to machines for resurfacing phonograph records, particularly records of the type intended for use with dictating machines. The invention is especially concerned with improvements in record resurfacing machines which will facilitate their operation and safeguard the machines from such improper use as may result in damage to the machine or to the records to be resurfaced.

10 Phonograph record resurfacing machines of the form abovementioned comprise a record support or mandrel, an endgate for the mandrel movable into operative or mandrel-supporting position, a carriage movable along the mandrel, and a resurfacing tool on the carriage settable into operative relationship to a record on the mandrel. When the tool is set a first or heavy cut will be taken from the record upon rotating the mandrel and feeding the carriage therealong, a suitable driving means being provided to concurrently effect the mandrel rotation and carriage feeding. At the completion of such first cut a suitable finishing-cut controlling means may be operated to advance the tool slightly towards the record so that a light or finishing cut may next be taken to obtain an added smoothness of the record surface. The resurfacing tool is a delicate instrument and is to be set on the record only under certain proper conditions in order to insure not only that a proper depth of cut will be made by the tool but also that the tool will not be set under such conditions as will cause damage to the tool or record.

It is an object of my invention to provide means to insure a proper setting of the tool on the record.

It is another object of my invention to provide means to prevent the operator from accidentally setting the tool under conditions which may result in damage to the machine or record to be resurfaced.

It is a further object of my invention to provide means to insure a uniform setting of the tool.

45 Another object of my invention is to provide means to insure that the finishing-cut controlling means will be in inoperative position as the tool is set.

50 It is another object of my invention to automatically return the finishing-cut controlling means to inoperative position by the release of the tool from a set position.

Another object of my invention is to automatically return both the tool and finishing-cut con-

trolling means to inoperative position upon the stopping of the machine.

It is a feature of my invention to prevent the setting of the tool on the record when either the machine is in operation or the endgate is out of a mandrel-supporting position.

Another feature of my invention is to provide means to permit a setting of the tool only when the carriage is in a predetermined position in its path of movement.

Other objects and features of my invention will more fully appear from the following description and the appended claims.

In the description of my invention reference is had to the accompanying drawings, of which:

Figure 1 is a top plan view of a phonograph record shaving machine in which my invention is incorporated;

Figure 2 is a vertical sectional view taken substantially along the line 22 of Figure 1;

Figure 3 is a horizontal sectional view taken substantially along the line 3—3 of Figure 2;

Figure 4 is a fractional vertical view, partly in section along the line 4—4 of Figure 2 and showing details of the means for controlling the setting of the tool;

Figure 5 is a front view of the mechanism of Figure 1, partly broken away and partly in section;

Figure 6 is a fractional, horizontal sectional view taken substantially along line 6—6 of Figure 5;

Figure 7 is a fractional, vertical sectional view taken substantially along the line 7—7 of Figure 5;

Figure 8 is a fractional top plan view of the mechanism of Figure 1, showing details of parts of my invention; and

Figure 9 is a front elevational view of parts of the mechanism of Figure 8, a portion of the frame of the machine being shown in dash-dot lines.

Reference being had to the figures, particularly Figures 1 and 2, there will be seen a phonograph record resurfacing machine comprising a frame having a base plate 1 with a left-hand standard 2, right-hand standards 3 and 4 and an intermediate standard 5. Pivoted on a boss 6, which extends up from the base plate to the right of the standard 4, is an endgate 7 normally held in closed position, as shown in Figure 1, by a latch 8 pivoted at 9 to the right end of a guide rail 10 which extends laterally along the forward part of the machine. Supported by the left standard 2 and by the endgate 7 are respective conically pointed studs 11 and 12 which form a pair of

left and right thrust bearings for rotatably supporting a shaft 13 in parallel relation to the guide rail 10. The shaft 13 passes through an oversized hole 14 in the standard 5 and carries a mandrel 5 15 for removably holding a cylindrical record 16 to be resurfaced. In the mounting of a record on, or the removal of a record from, the mandrel the endgate is first swung open to free the right end of the mandrel. When the endgate is open 10 the shaft 13 is intermediately supported by the standard 5—the mandrel being permitted to fall a small distance—but is retained in engagement with the stud 11 by the abutment of a collar 17, secured to the shaft by a screw 17', against the 15 left side of the standard 5.

The mounting of a record on the mandrel is done by manually placing the record in a position on the mandrel wherein the record telescopes the mandrel. The removal of the record 20 from the mandrel is, however, done by means of an ejector. This ejector is well known in the art and is sufficiently described in the present instance as follows: A handle 18 is integrally formed with an upright arm 19 and is pivoted on 25 a pin 20 which is supported at one end by the intermediate standard 5 and at the other end by the guide rail 10. The arm 19 carries a shoe 21 lying to the left of the record but normally held out of contact with the record by a torsional 30 spring 22, constrained at one end by the base plate and at the other end by the handle 18, which retains the ejector in unoperated position. When the ejector is operated, as by lifting the handle 18, the shoe 21 is moved against the 35 record to push the record off the mandrel. Yieldably connected with the arm 19 of the ejector 18, by a torsional spring 23, is a mandrel brake 24 carrying a shoe 25. As the ejector is operated the shoe 25 is yieldably pressed against the left 40 end of the mandrel to retard the mandrel against rotation. For a detailed description of this combination of record ejector and mandrel brake, reference is had to Huenlich Patent No. 2,128,646, issued August 30, 1938 and entitled "Braking and 45 ejecting mechanisms."

Supported by the left and right standards 2 and 4, in parallel relation to the guide rail 10, is a rod 26 on which there is slidably and tiltably mounted a carriage 27 having a sleeve 27' embracing the rod. The carriage 27, which may be a casting, comprises a relatively narrow arm 28 extending up from the rod 26 and an arm 29 extending forwardly from the arm 28 over the mandrel 15, the arm 29 terminating in a shoe 29' which normally slidably rests on the guide 55 rail 10. The arm 29 is increased in width in a rightward direction, as at 29'', and is hollowed out from the underside to provide a recess 30 in which there is provided a mechanism hereinafter described. To move the carriage steadily in a 60 leftward direction along the mandrel (as from a start position at the right end of the mandrel into a terminal position at the left end of the mandrel) coincidentally with a rotation of the mandrel, there is provided a laterally extending 65 feed screw 31 rotatably supported by the left and right standards 2 and 3 and having a pulley 32 adapted to be coupled, as by a belt (not shown), to a pulley 33 on the shaft 13. Secured to the carriage sleeve 27', by the screws 34, is a rearwardly extending spring arm 35 carrying a feed nut 36. This feed nut is held in engagement with the feed screw 31 whenever the carriage arm 29 is resting on the guide rail; however, whenever the carriage arm 29 is raised to 70

tilt the carriage the feed nut 36 is moved downwardly out of engagement with the feed screw, thereby freeing the carriage so that it may be manually moved along the mandrel at will. To limit the upward tilting of the carriage there 5 is provided on the carriage a downwardly extending post 37 which is adapted to impinge against a ridge 38 provided on the base plate.

On the right side of the arm 28 of the carriage 10 27, substantially overlying the rod 26, is an extension 39 which is square-shaped as viewed from the end. The extension 39 supports a resurfacing tool comprising a knife bar 40 and a knife blade 41 provided at the inner end of the bar. The bar 40 is slidably mounted for radial movement 15 relative to the record. The means for setting the resurfacing tool into operative position—a position in which the knife blade 41 engages the record—and for releasing the same may comprise the well-known construction disclosed in Brown 20 Patent No. 2,137,383, issued November 22, 1938 and entitled "Record shaving machine."

In the construction abovementioned the knife bar 40 is biased away from the record, and, in the setting of the tool, is yieldably moved towards, the record into operative position, the tool being then locked in such position. This tool-setting means is sufficiently described by the following statements: A cap 42 is secured to a guide rod 43 which is slidably supported by the extension 39 in parallel relation to the knife bar 40. The knife bar 40 passes through the cap 42 and terminates in a head 44. The cap 42 is biased upwardly by a compression spring 45 coiled about the guide rod 43 between the extension 39 and the 30 cap 42. This upward biasing of the cap causes the resurfacing tool to be normally maintained in inoperative position, as by the contact of the cap 42 with the head 44, the inoperative position of the tool being defined by the contact of a 40 collar 40' on the knife bar with the underside of the extension 39. When the cap 42 is moved towards the record the knife bar 40 is yieldably moved therewith by means of a compression spring 46 coiled about the knife bar between a 45 shoulder 40'' on the bar and the cap 42. The cap 42 is controlled by a lever 47 pivoted as at 48 on the right side of the extension 39 and coupled to the cap 42 by an angular link 49 which is pivoted by a pin 50 to the lever 47 50 and by a shoulder screw 51 to an ear 52 turned over from the cap 42.

When the lever 47 is turned in a counter-clockwise direction the cap 42 is moved downwardly to move the tool into operative position, relative to 55 the record, the terminal movement of the lever causing a pin 53 to be pressed against the knife bar 40 to lock the tool in its operative position, as is described in the abovementioned Brown patent. The terminal position of the lever 47, 60 shown in Figure 2, is defined by the impingement of the link 49 against the hub 41' of the lever 47. When the lever 47 is in this terminal position, the pivot or pin 50 is slightly past dead center with respect to the pivot axes of the lever 47 and 65 of the screw 51. The lever 47 is then urged in a counter-clockwise direction into its terminal position by the upward biasing of the cap 42. Thus the lever is releasably held in its terminal position, the tool being then locked in its operative position. When the lever 47 is, however, tripped—i. e., moved slightly in a clockwise direction to return the pin 50 across the dead center line abovementioned—the upward biasing of the 70 cap 42 will cause the tool to be unlocked, as by 75

the clockwise turning of the lever 42, and then returned to inoperative position. This tool setting and releasing means may be suitably enclosed by a cover 28' fitting the carriage.

5. When the tool has been set into operative position and the carriage has been returned to start position the machine may be put into operation to cause a first or heavy cut to be taken from the record, this cut-away layer—commonly known as 10 shaving chips—being carried by a chip chute 54 downwardly through an opening 54' in the base plate, as for example, into a suitable container (not shown). The driving means for the machine—i. e., the means for rotating the mandrel 15 and feeding the carriage—may comprise a suitable electrical drive motor (not shown) which may be located beneath the base plate 1 and be coupled to a pulley 55 on the shaft 13 as by a belt (not shown) which may pass through an opening 20 56 in the base plate.
20. The drive motor may be controlled by a suitable single-pole single-throw switch 57, preferably of the toggle variety, which may be secured to the underside of the base plate 1 by a bracket 25 58 in the forward right-hand portion of the plate. The switch 57 may be manipulated into its "on" and "off" positions by a forwardly extending lever 59 pivoted in a boss 60 extending downwardly from the base plate and connected by a shoulder 30 screw 61 to a rearwardly extending arm 62. The arm 62 carries a slotted, pivoted stud 63 through which slidably passes an actuating arm 64 of the switch 57. When the lever 59 is moved leftwardly and rightwardly the arm 64 is moved rightwardly and leftwardly to throw the switch 57 into its respective "on" and "off" positions, the lever 59 snapping into its respective leftward and rightward position by reason of the toggle nature of the switch.
40. After a first cut has been taken on the record it may be desirable to take another cut of a light or finishing character in order to obtain an added smoothness of the record. To facilitate the taking of such a finishing cut there is provided a 45 finishing-cut controlling means which is operable to advance the resurfacing tool a slight distance towards the record without disturbing the setting of the tool. This finishing-cut controlling means comprises a short rod 65 mounted for pivotal movement about its longitudinal axis and extending through the shoe 29' of the carriage 27 in parallel relation to the guide rail. The rod 65 projects radially along its length below the shoe 29' throughout a minor portion of its periphery. 50 Thus the carriage arm 29 is normally supported by the guide rail by way of the rod 65. The rod 65 is provided with a flat 66 throughout its length, but the rod is normally turned into a position wherein the flat 66 is out of contact with the guide 55 rail. When the rod is, however, turned to bring the flat into contact with the guide rail the carriage arm 29 is lowered slightly to advance the tool towards the record. The rod 65 is manually controlled by means of a bracket 67 on the rod 65. When the bracket is in a forwardly extending 60 position as shown in Figure 2, the flat 66 is off the guide rail and the finishing-cut controlling means is therefore in inoperative position; when the bracket is, however, moved into an upward inclined position as shown in dash-dot lines in 70 Figure 2, the flat 66 is brought into contact with the guide rail to place the finishing-cut controlling means into operative position.
75. The above-described structure and mechanism are common to record shaving machines hereto-

fore manufactured and used, and form a part of the present invention only in so far as they are related to or combined with other mechanism hereinafter described.

In preparing a record shaving machine for a record resurfacing operation the carriage is moved into an appropriate position along the record—usually a position wherein the resurfacing tool overlies the record—the tool is set into operative position relative to the record, and then the carriage is manually returned to start position. It is an object of my invention to facilitate the performance of the above operations by the provision of a fingerpiece on the carriage which is adapted to facilitate the manual movement of the carriage and which is moreover movable relative to the carriage to effect a setting of the resurfacing tool, thereby permitting the operator to grasp a single member (the fingerpiece) on the machine and perform both the manual movement of the carriage and the setting of the tool by manipulations of that member.

Reference being had to Figures 1, 2, 3 and 5 there will be seen a fingerpiece 68 projecting forwardly from the carriage arm 29. This fingerpiece is carried by a relatively heavy member 69 (suitably a casting) disposed within the recess 30 in the carriage arm 29 and provided with a pair of left and right rearwardly and downwardly extending legs 69' and 69'' which are pivoted on a pair of left and right trunnions 70 and 71 carried by the left and right walls of the carriage arm 29, the fingerpiece 68 having an arm 68', extending through a long vertical opening 72 in the forward part of the carriage arm 29, which is secured by the screws 73 to the member 69. The member 69 is biased upwardly against the top of the carriage arm 29 to normally retain the fingerpiece 68 in its most upward position, shown in Figure 2, this biasing being effected by a tension spring 74 connected between the left leg 69' of the member 69 and a pin 75 on the carriage arm. Thus manipulation of the carriage may be conveniently effected by grasping the fingerpiece 68 to tilt the carriage upwardly and to then move the carriage into the position desired. When the carriage is next lowered on the guide rail the fingerpiece 68 may be next moved downwardly to cause a setting of the resurfacing tool without disturbing the carriage in its position, as hereinafter described, after which the carriage may be returned by the fingerpiece 68 to start position.

In order that a downward movement of the fingerpiece 68 relative to the carriage may cause the resurfacing tool to be set, there is provided in the recess 30 a long angular arm 76 which is pivoted by a screw 77 to a boss 78 in the forward part of the carriage arm 29. The arm 76 extends rearwardly from its axis throughout the length of the carriage arm 29, is offset to the right as at 79, and terminates in a fork 80 having an open slot 81. Provided on the tool-setting lever 47 is a pin 82 which slidably engages the slot 81. When the arm 76 is swung downwardly the lever 47 is turned in a counter-clockwise direction to cause a setting of the tool. In order that a downward movement of the fingerpiece 68 may cause such downward swinging movement of the arm 76 there is pivoted on the member 69 between the legs 69' and 69'', as on a pin 83, a roller 84 which impinges upon a cam face 85 on the arm 76 as the member 69 is moved downwardly by the fingerpiece 68. When the resurfacing tool has been set the fingerpiece 68, upon its release, will return to its upward position.

tion as by reason of its biasing; the arm 76 will, however, be retained in its downward, or operated, position by reason of the tool-setting lever 47 being releasably held in its operated position, as heretofore described.

Due to a possible out-of-alignment between the path of the carriage—which path is determined by the guide rail 10 and the longitudinal rod 26—and the mandrel shaft 13, it is important that the carriage be in some one predetermined position in its path each time the resurfacing tool is set into operative position in order to insure that a uniform depth of cut along the record will be obtained for each record resurfacing. In accordance with my invention I provide means for preventing a setting of the resurfacing tool except when the carriage is in such predetermined position, this position of the carriage being preferably at a point substantially midway of its path of movement as is indicated in Figure 5.

The means for restricting the setting of the tool to a predetermined position of the carriage comprises a slide member 86 (see Figure 2) which is mounted for vertical movement within the recess 30 of the carriage arm 29 by a pair of cross pins 87 carried by the carriage and passing slidably through a long vertical slot 88 in the slide member, the slide member 86 being retained on the pins 87 at a point substantially midway of the width of the recess 30 by means of tubes or spacers 89 which embrace the pins. Integrally formed with the slide member 86 is a rearwardly extending arm 90 which terminates in an open slot 91 embracing a pin 92 carried by the angular arm 76 substantially midway of its length, the slide member 86 being thus coupled with the arm 76 so as to cause the slide member to be moved upwardly and downwardly with the upward and downward swinging of the arm. On the slide member there is pivoted, as at 93, an arm 94 which extends downwardly just to the rear of the guide rail 10 and which terminates in a foot 95. The arm 94 is biased forwardly into a position defined by the contact of an ear 94' on the arm with a face 96 on the rear of the carriage shoe 29 as by a tension spring 97 connected between the slide member 86 and the ear 94', rearward movement of the arm being limited by the contact of a lug 98, turned over from the arm 94, with the rear edge 86' of the slide member. Provided along the guide rail is a rearwardly extending ledge 99. When the resurfacing tool is in a set position the foot 95 is below the ledge 99 as shown in Figure 2, the foot 95 being yet below the ledge even when the carriage arm 29 is moved into its upwardly tilted position. However, when the resurfacing tool is released to inoperative position the slide member 86 is moved upwardly by the arm 76 to bring the foot 95 of the arm 29 into a position overlying the ledge, the foot sliding over the ledge and then snapping forwardly by reason of its biasing. When the foot 95 is above the ledge 99 the slide member 86 is locked against downward movement, thereby preventing a setting of the tool. The ledge 99 is, however, provided with an opening 100 which is positioned so that when the carriage is in its predetermined position abovementioned, the foot 95 directly overlies the opening 100. This opening is large enough to permit the foot 95 to pass freely therethrough so as not to obstruct the slide member 86 against downward movement, thereby permitting a setting of the resurfacing tool when the carriage is in its predetermined position.

In order that the carriage may be readily

located in this predetermined position wherein a setting of the tool is permitted, I provide means for stopping the return movement of the carriage to this position. This stopping means comprises a stop member 101 (see Figure 8) slidably mounted on the top side of the base plate to the rear of the carriage by means of a shoulder screw 102 which passes through a slot 103 in the stop member. The stop member has a forwardly extending arm 104 provided with a turned-up lug 104' which lies directly behind the ridge 38 on the base plate. The stop member 101 is biased leftwardly and in a counter-clockwise direction about the screw 102 by means of a tension spring 105 connected between the stop member and a pin 105' on the base plate, the leftward position of the stop member being defined by the contact of the screw 102 with the end of the slot 103 and the counter-clockwise turning of the stop member being limited by the contact of an upright pin 106 on the base plate with an arm 107 on the stop member. As the carriage is manually moved along the record the post 37 on the carriage—which post has its lower end portion milled to form left and right flat faces 37' and 37'' thereon—slides along the ridge 38 to define the upward tilted position of the carriage. When the carriage is returned from its terminal position the face 37'' of the post 37 impinges against the lug 104' and moves the stop member 101 rightwardly against its biasing until the stop member is limited by the screw 102. The return of the carriage is then stopped, the stop member 101 being so positioned as to cause this stopping of the carriage to occur in the predetermined position above mentioned. When the carriage arm 29 is lowered on the guide rail the face 37'' of the post 37 is moved free of the lug 104'; the stop member 101 then moves leftwardly, as because of its biasing, to bring the lug 104' into a position to the left of the post 37. The carriage arm 29 may then be again tilted upwardly and its return movement resumed. If the carriage should be manually moved to the left the leftward face 37' of the post 37 will impinge against the lug 104' to turn the stop member 101 in a clockwise direction. As the stop member 101 is so turned the lug 104' snaps over the post 37, thereby freeing the carriage of the stop member to permit further leftward movement of the carriage.

The resurfacing tool may be properly set only when the mandrel is stationary and properly supported—the conditions present when the machine is out of operation and the endgate is closed—and when the finishing-cut controlling means is in inoperative position. In accordance with my invention, a proper setting of the tool is insured by the provision of means for preventing a tool-setting whenever either the machine is in operation or the endgate is open, and by the provision of means for resiliently maintaining the finishing-cut controlling means in inoperative position so long as the tool is released, thereby in practice normally insuring a setting of the tool only when the finishing-cut controlling means is in operative position. This means for preventing an improper setting of the tool may very suitably be in the form of a controllable gate for closing the opening 100 in the ledge 99 since in view of the mechanism heretofore described a tool-setting is possible only by reason of the opening 100.

Reference being had to Figures 5, 6, 7, and 8, it will be seen that the guide rail 10 is cut away below the opening 100 to form a recess 108 in

which there is disposed a vertical arm 109 having at its upper end a turned-back lug forming a gate 110 for the opening 100. The arm 109 is provided with turned-over ears 111, at its lower end, which are pivoted by a cross pin 112 to a bracket 113 secured to the base plate. When the arm 109 is tilted backwardly the gate 110 closes the opening to thereby prevent a setting of the tool, but when the arm 109 is tilted forwardly the gate 110 is free of the opening 100 to then permit a tool setting.

In order that a tool setting will be prevented when the machine is in operation, the arm 109 is coupled to the switch 57 so that the opening 100 will be closed by the gate 110 when the switch 57 is in "on" position. This coupling means comprises a slide member 114 (see Figures 8 and 9) disposed below the guide rail 10 at the underside of the base plate and mounted for lateral movement, the member 114 being slidably retained to a pair of bosses 115, extending downwardly from the base plate, by a pair of shoulder screws 116. The slide member 114 partially overlies the arm 62 of the switch-control means and is coupled to this arm by means of a vertical pin 117 on the arm which passes through a cross slot 118 in the slide member, the slide member being thus moved rightwardly and leftwardly as the control lever 59 is moved leftwardly and rightwardly to place the switch 57 into "on" and "off" positions. Turned up from the slide member 114 is a lug 119 which extends through an opening 119' in the base plate. Extending along the right half portion of the guide rail 10 is a bar 120 which is pivoted at a point substantially midway of its length, as by a pin 121, to the lug 119. At the left end of the bar 120 there is provided an angular longitudinal slot 122 which is curved upwardly in proceeding rightwardly along the slot, as shown in Figure 9, and which is engaged by a short arm 123 extending rearwardly from one of the ears 111 of the arm 109, as shown in Figure 7. While the bar 120 is pivotally supported its pivoted movement is limited or guided by a pin 124 on the guide rail which passes through a longitudinal slot 125 provided in the right end portion of the bar.

When the switch 57 is in "off" position, the control lever 59 being then in the position shown in Figure 8, the bar 120 is in its most leftward position with the pin 123 engaging the upward right end portion 122' of the curved slot 122. The arm 109 is then held in a forwardly tilted position to render the gate 110 free of the opening 100, thereby permitting a setting of the resurfacing tool. When the control lever 59 is moved leftwardly to place the switch 57 in "on" position, the bar is moved rightwardly with the pin 123 coming to rest in the lower left end portion 122'' of the curved slot 122. The arm 109 is then held in a rearwardly tilted position wherein the gate 110 closes the opening 100, thereby locking the tool-setting means to prevent a setting of the tool.

In order that the arm 109 may also be tilted rearwardly to close the opening 100 by the gate 110 when the machine is stopped and the endgate is open, the right end portion 120' of the bar is extended rightwardly beyond the guide rail at a level just below the endgate (see Figure 9). The bar 120 is also biased in a counter-clockwise direction by a tension spring 126 connected between the bar and the slide member 114, and at the right end portion of the slot 125 there is provided a downwardly extending

notch 127 to permit a limited counter-clockwise movement of the bar 120 when the bar is in its leftward position, the position of the bar when the switch 57 is in "off" position. When the endgate is closed the bar 120 is held in its normal position by the contact of the right end portion 120' of the bar with the endgate. The arm 109 of the gate 110 is then tilted forwardly to render the opening 100 free of the gate 110. However, when the endgate is opened the right end portion 120' of the bar 120 is tilted upwardly, by the spring 126, until the pin 124 engages with the notch 127. As the bar 120 is so tilted the pin 123 of the arm 109 is moved downwardly and the arm 109 is moved rearwardly to cause the opening 100 to be closed by the gate 110, thereby locking the tool-setting means as heretofore described.

In order that the release of the resurfacing tool from operative position may cause the finishing-cut controlling means to be restored to inoperative position the foot 95 of the arm 94 is provided with a cross pin 128 and the finishing-cut controlling means is provided with a rearwardly extending pin 129. As the bracket 67 of the finishing-cut controlling means is moved upwardly into operative position the pin 129 is swung downwardly. Upon the release of the tool from a set position the slide member 86, which carries the arm 94, is moved upwardly, as heretofore described. In the terminal movement of the slide member the pin 128 impinges upon the pin 129 to move the bracket 67 downwardly, thereby placing the finishing-cut controlling means in inoperative position. Since the slide member 86 is biased upwardly when the tool is released, as by the spring 45 which urges the tool into its released or inoperative position, the finishing-cut controlling means is yieldably held in inoperative position so long as the tool is not set, thereby in practice insuring against accidental setting of the tool while the finishing-cut controlling means is in operative position.

The means for releasing the resurfacing tool from operative position is operated by throwing the switch 57 to "off" position to stop the machine, and comprises a bar 130 disposed behind and along the guide rail throughout the length of the path of movement of the carriage, the bar being slidably mounted on left and right bosses 131 and 132 on the guide rail by the shoulder screws 131' and 132' which pass through respective slots 131'' and 132'' in the bar to thread into the respective bosses. The slots 131'' and 132'' are parallel to each other and are at a substantially 45° angle from a vertical line so that the bar will have both vertical and lateral components of movement. When the bar is in its most downward position, this being also its most rightward position, as shown in Figure 5, the bar is slightly below the position occupied by the foot 95 when the resurfacing tool is set, as is indicated in Figure 2. The bar 130 is normally held in this most downward and rightward position by means of a tension spring 133 connected between the bar and a pin 133' on the guide rail. At the right end portion of the bar 130 there is provided a downwardly extending ear 134 (see Figure 4) on which is pivoted, by a screw 135, a short V-shaped pawl 136. The pawl 136 extends downwardly through the opening 119' in the base plate and is biased by a spring 137 in a clockwise direction into a position defined by the abutment of a top lug 138 on the pawl with the ear 134. On the arm 62 of the operating means

for the switch 57 there is provided a turned-up lug 139. When the switch 57 is in "on" position and the bar 130 is in its downward or unoperated position the lug 139 is slightly to the right of the pawl 136, as shown in Figure 5. When the switch 57 is thrown to "off" position the arm 62 is moved to the left and the lug 139 is impinged against the pawl 136 to cause the bar 130 to be moved leftwardly and upwardly. The upward component of movement of the bar causes, as by the contact of the bar with the foot 95, an upward movement of the slide member 86 and of the arm 76, thereby imparting a clockwise or tripping movement to the tool-setting lever 47 to cause both the release of the tool and the biasing of the finishing-cut controlling means to inoperative position as heretofore described. The bar 130 is moved sufficiently upwardly to render the pawl 136 free of the lug 139 before the lug reaches the end of its travel in the throwing of the switch 57 to "off" position. When the pawl 136 becomes free of the lug 139 the bar 130 is returned by the spring 133 into its downward or unoperated position. When the switch 57 is later thrown to "on" position, no movement is imparted to the bar since the lug 139, in its rightward movement, merely encounters an inclined cam face 136' on the pawl 136 and turns the pawl out of its path of movement, the pawl then snapping back into its normal position as because of the spring 137.

The above-described tool-releasing means is not effective when the carriage arm 29 is in an upwardly tilted position since the foot 95 is then out of the path of the bar 130. Thus when the carriage is held in an upwardly tilted position the machine may be stopped without releasing the tool. The tilting of the carriage for the purpose of avoiding the release of the tool by the stopping of the machine will, in practice, be done when, at the completion of a first cut on the record, the machine is stopped for the purpose of inspecting the surface of the record to determine if a finishing cut is necessary. If a finishing cut is found desirable the carriage will be returned to start position in the usual manner and the machine will be restarted to take the finishing cut. If, however, it is not found desirable to take a finishing cut the carriage will be lowered on the guide rail at its terminal position and the record will be ejected from the machine. In order that such lowering of the carriage may cause the release of the tool from its set position, so as in practice to insure that the tool will be released when the carriage is later returned for the purpose of resetting the tool, there is provided at the left end portion of the guide rail a rearwardly extending ledge 140 which is positioned below the ledge 99, as shown in Figures 1 and 2. When the carriage arm 29 is moved into its upwardly tilted position, while the carriage is in its terminal position and the tool is in a set position, the foot 95 is caused to snap over the ledge 140. If the carriage is next returned the foot 95 is moved off of the ledge 140, but if the carriage arm 29 is next lowered on the guide rail while the carriage is yet in its terminal position the foot 95 is moved upwardly relative to the carriage, by reason of its contact with the ledge 140, to cause the release of the tool.

Although I have herein shown and described one embodiment of my invention, it will be understood that this embodiment is subject to many changes and modifications without departure

from the scope of my invention, which I undertake to express according to the following claims.

I claim:

1. In a phonograph record resurfacing machine having a record support: the combination of a carriage movable along said support; a resurfacing tool on said carriage settable into operative position relative to a record on said support; tool-setting means; and means, associated with said tool-setting means, for rendering said tool-setting means inoperable except when said carriage is in a predetermined position in its path. 10

2. In a phonograph record resurfacing machine having a record support: the combination of a carriage movable along said support; a resurfacing tool on said carriage settable into operative position relative to a record on said support; tool-setting means; and means, extending along a portion of the path of said carriage and operatively associated with said tool-setting 15 means, for rendering said tool-setting means inoperable for all positions of said carriage within said portion of its path. 20

3. In a phonograph record resurfacing machine having a record support: the combination of a carriage movable along said support; a resurfacing tool on said carriage settable into operative position relative to a record on said support; tool-setting means on said carriage; and restricting means for said tool-setting means comprising an obstructing member extending along a portion of the path of said carriage and means operatively connecting said tool-setting means with said obstructing member whereby said tool-setting means is rendered inoperable while said carriage is within said portion of its path. 35

4. In a phonograph record resurfacing machine having a record support: the combination of a carriage adapted to be driven and otherwise manipulated along said support; a resurfacing tool on said carriage settable into operative position relative to a record on said support; tool-setting means mounted on said carriage; a fingerpiece extending forwardly from said carriage and adapted to be grasped to manipulate the carriage, 40 said fingerpiece being mounted for movement relative to said carriage in a direction transversely of the direction of movement of said carriage; and means, operatively connecting said tool-setting means with said fingerpiece, for causing said tool-setting means to be operated by the movement of said fingerpiece relative to said carriage. 45

5. In a phonograph record resurfacing machine having a record support: the combination of a slidably mounted and upwardly tiltable carriage 50 adapted to be slidably manipulated along said support when retained in an upwardly tilted position; a resurfacing tool on said carriage settable into an operative position relative to a record on said support; a fingerpiece on said carriage adapted to be grasped to tilt the carriage upwardly and to manipulate the same across said support; and means, connecting said fingerpiece with said resurfacing tool, for causing a setting 55 of the tool by a downward movement of said fingerpiece relative to said carriage. 60

6. In a phonograph record resurfacing machine having a record-supporting mandrel; the combination of an endgate movable into and out of 65 a mandrel-supporting position; a resurfacing tool settable into operative position relative to a record on said mandrel; tool-setting means; and means, operatively connected with said endgate, for rendering said tool-setting means ineffective while 70 75

- 5 said endgate is out of its mandrel-supporting position.
- 6 7. In a phonograph record resurfacing machine having a record-supporting mandrel: the combination of an endgate movable into and out of a mandrel-supporting position; a resurfacing tool settable into operative position relative to a record on said mandrel; tool-setting means; and means, controlled by said endgate, for locking 5 10 said tool-setting means against operation.
- 11 8. In a phonograph record resurfacing machine having a record-supporting mandrel: the combination of a movable endgate for said mandrel; a carriage movable along said mandrel; a resurfacing tool on said carriage settable into operative position relative to a record on said mandrel; tool-setting means; means for rendering said tool-setting means inoperable for all selected 15 20 positions of said carriage within a portion of its path of movement; and means, controlled by said endgate, for controlling said tool-setting means when said carriage is out of said portion of its path.
- 21 9. In a phonograph record resurfacing machine 25 having a record-supporting mandrel: the combination of a movable endgate for said mandrel; a control means movable into "on" and "off" positions to start and stop the operation of the machine; a resurfacing tool settable into operative position relative to a record on said mandrel; tool-setting means; and means, jointly controlled by said endgate and said control means, for rendering said tool-setting means ineffective to set said tool.
- 26 10. In a phonograph record resurfacing machine having a record support: the combination of a control means movable into "on" and "off" 30 35 positions to start and stop the operation of the machine; a resurfacing tool settable into operative position relative to a record on said support; means for setting said tool; and means, operated incidental to the movement of said control means to "on" position, for rendering said tool-setting means inoperable.
- 40 11. In a phonograph record resurfacing machine having a record support: the combination of a control means movable into "on" and "off" 40 45 positions to start and stop the operation of the machine; a resurfacing tool settable into operative position relative to a record on said support; tool-setting means; and means for preventing setting of said tool during the operation of the machine comprising locking means for said tool-setting means and means, operatively connecting said locking means with said control means, for rendering said locking means operative when said control means is in "on" position.
- 46 12. In a phonograph record resurfacing machine having a record support: the combination 50 55 of a control means movable into "on" and "off" positions to start and stop the operation of the machine; a carriage movable along said support; a resurfacing tool on said carriage settable into operative position relative to a record on said support; tool-setting means; means for rendering said tool-setting means inoperable while said carriage is out of a predetermined portion of its path of movement; and means, rendered operative incidental to the movement of said control 60 65 70 means to "on" position, for rendering said tool-setting means inoperable when said carriage is within said predetermined portion of its path.
- 75 13. In a phonograph record resurfacing machine having a record support: the combination 75 of a control means movable into "on" and "off" 75 positions to start and stop the operation of the machine; a resurfacing tool movable into operative and inoperative positions relative to a record on said support; means for moving said tool to operative position; and means, operated by said control means, for causing said tool to be moved to inoperative position by the movement of said control means to "off" position and for rendering said tool-moving means inoperable when said control means is in "on" position. 10
- 80 14. In a phonograph record resurfacing machine having a record support: the combination of a resurfacing tool settable into operative position relative to a record on said support and releasable therefrom; finishing-cut controlling means movable into operative position to advance said tool a predetermined distance towards the record; and means, operatively connecting said tool with said finishing-cut controlling means, for moving the finishing-cut controlling means out of operative position upon the release of said tool. 15 20
- 25 15. In a phonograph record resurfacing machine having a record support: the combination of a resurfacing tool settable into operative position relative to a record on said support and releasable therefrom; finishing-cut controlling means movable into operative position to advance said tool a predetermined distance towards the record; and means, rendered effective 30 upon the release of said tool, for biasing said finishing-cut controlling means out of operative position. 35
- 40 16. In a phonograph record resurfacing machine having a record support: the combination of a resurfacing tool having operative and inoperative positions relative to a record on said support; means for releasably locking said tool in operative position; finishing-cut controlling means movable from inoperative to operative position to advance said tool towards the record; and biasing means, rendered effective as an incident to the release of said tool-locking means, for moving both said tool and said finishing-cut controlling means to their respective inoperative 45 positions. 45
- 50 17. In a phonograph record resurfacing machine having a support for a record to be resurfaced: the combination of an "on" and "off" control means for the machine; a resurfacing tool settable into operative relationship to the record and releasable therefrom; a finishing-cut controlling means movable from inoperative to operative position to advance said tool towards the record; and means, operated incidental to 55 the movement of said control means to "off" position, for releasing said tool and concurrently causing said finishing-cut controlling means to be moved into inoperative position. 60
- 60 18. In a phonograph record resurfacing machine having a record support: the combination of a resurfacing tool settable into operative relationship to a record on said support; a finishing-cut controlling means movable from inoperative to operative position to advance said tool towards the record; and means, controlled by said tool, for moving said finishing-cut controlling means to inoperative position. 65
- 70 19. In a phonograph record resurfacing machine having a record support: the combination of a carriage adapted to be driven and otherwise manually moved along said support; a resurfacing tool on said carriage; means, operable only when said carriage is in a predetermined portion of its path, for setting said tool into oper- 75

ative position relative to a record on said support; and means for locating said carriage to permit the setting of the tool comprising a stop for interrupting the manual movement of said carriage 5 when the carriage is moved into said predetermined portion of its path.

20. In a phonograph record resurfacing machine having a record support: the combination of a carriage movable along, and tiltable away 10 from and towards, said support; a resurfacing tool on said carriage settable into operative relationship to a record on said support and releasable therefrom; and means for causing a release of said tool from a set position by a tilting movement of said carriage towards the record.

21. In a phonograph record resurfacing machine having a record support: the combination of a carriage movable along, and tiltable in directions normal to, said support; a resurfacing 20 tool on said carriage settable into operative relationship to a record on said support and releasable therefrom; and means, operated by said carriage, for causing a release of said tool from a set position as an incident of a to and fro movement of said carriage away from and towards 25 said record support.

22. In a phonograph record resurfacing machine having a frame and a record support rotatably mounted on said frame; the combination of 30 a carriage mounted on said frame to slide along said record support and to tilt upwardly and

downwardly relative to said support; a resurfacing tool on said carriage settable into operative relationship to a record on said support and releasable therefrom; tool-releasing means, and means mounted on said frame and coacting with 5 said tool-releasing means to cause operation thereof as an incident to a downward tilting of said carriage.

23. In a phonograph record resurfacing machine having a record support: the combination 10 of a carriage movable along, and tiltable upwardly and downwardly relative to, said support; a resurfacing tool on said carriage settable into operative relationship to the record and releasable therefrom; and means, operated by said carriage and rendered effective as an incident to an upward tilting of the same, to cause the release 15 of said tool from set position upon a downward tilting of the carriage.

24. In a phonograph record resurfacing machine having a record support: the combination 20 of a tiltably mounted carriage movable along said support; a resurfacing tool on said carriage settable into operative relationship to the record and releasable therefrom; and means, effective 25 when said carriage is in a predetermined portion of its path along said support, for causing the release of said tool from a set position by a tilting of said carriage.

LOUIS Z. LA FOREST.
